UNITED STATES PATENT OFFICE

DENT FERRELL AND ARTHUR W. HELMHOLTZ, OF HARRISBURG, ILLINOIS, ASSIGNEES
TO SAFETY MINING COMPANY, OF CHICAGO, ILLINOIS, A CORPORATION OF ILLINOIS

BLASTING MECHANISM

Application filed June 23, 1928. Serial No. 287,865.

This invention relates to blasting cartridges, and particularly to new and useful means purely mechanical in operation for detonating, igniting, or starting a detonating cap, igniting a chemical compound capable of large heat liberation, or starting such chemical reaction as will result in a large heat liberation, whereby a body of fluid in the compressed and liquid state surrounds the heating element contained in the cartridge, is heated and at the same time agitated to such an extent that a pressure rise occurs in the compressed fluid sufficient to rupture a wall of the rigid container.

15 This invention relates particularly to a modification of the invention set forth in our co-pending application, Serial No. 169,441, filed February 19, 1927, entitled Blasting cartridges, in which carbon dioxide is preferably employed, confined in a rigid container of seamless drawn steel having an end wall or disk capable of being ruptured at a predetermined pressure, less than the bursting strength of the container itself.

25 The compressible fluid is gaseous at ordinary temperatures and pressures and is introduced into the container under such temperature that the fluid is liquid throughout its volume. The means by which this is accomplished is 30 fully disclosed in the co-pending application referred to and therefore will not be described in detail here.

In practicing the invention it is essential that the quantity of fluid in liquid state 35 placed in the container be under pressure less than the bursting strength of the wall or disk which is ruptured under discharge. The wall or disk is designed to rupture at a predetermined pressure, and it is therefore

40 necessary, when discharge is to be effected, that the compressed fluid or blasting medium be caused to exert greater pressure by supplying artificial heat thereto accompanied by excessive agitation. The heating and agitation should be so rapid that the pressure rise of the fluid medium, the rupturing of the weaker end wall or disk, the escape of the gasified fluid from the rigid container into the drill hole in the coal or other body 45 to be broken down, as well as the breaking

down of the coal or other body, are all accomplished in a comparatively instantaneous time interval. For the purpose of the above sequence of events means are provided for supplying sufficient heat to the compressed medium from a source which is contained within the cartridge so that the requisite heat accompanied by violent agitation is imparted directly to the blasting medium and its pressure thereby raised to the desired point.

In the applicants' prior application, and in their Patent No. 1,610,274, various means are disclosed for accomplishing the heating of the blasting medium. As disclosed in the patent the means for heating and agitating may be a fusible metallic conductor, or as disclosed in the application, it may be a chemical compound or suitable ingredients having a metallic conductor in its midst suitably connected to terminals for the passage of an electric current. In the latter form, the conductor is volatilized and forcibly disseminated throughout the body of the chemical compound and in this manner behaves as an ordinary cap detonator, in that heat sufficient to start the chemical reaction is derived from the volatile metallic conductor. It is also possible to utilize ordinary black gunpowder suitably confined in a receptacle carrying a relatively small metallic conductor throughout its volume, the conductor being suitably attached to terminals on the rigid container. By selecting the conductor small enough it is possible to set off the powder charge by the use of a weak current at very low voltage such as can be gotten from dry batteries or the like.

The above methods are found to be quite successful, but in some instances it has been found desirable to provide a means whereby the cartridge may be discharged by a purely mechanical means with results substantially similar to the results produced by an electric current.

Accordingly, it is the principal object of this invention to provide a cartridge of the above described type adapted to be discharged by purely mechanical means which

is simple in construction, cheap to manufacture and efficient in operation.

It is also an object to provide the necessary structural details for producing a cartridge of this type, such as means surrounding the concussion rod at its point of introduction into the interior of the casing for preventing loss of fluid and reduction in pressure, and also means for holding the heating element and detonating cap, together with a valved inlet through which the blasting medium is introduced.

It is a further object of this invention to provide an elongated rod extending from the blasting cartridge throughout the length of the drill hole and therebeyond to some remote location from which an operator may safely manipulate it, and to further provide means on the rod which will prevent accidental movement of the rod such as might effect discharge, which means will assure safety but will permit the rod to move and the cartridge to be set off when the rod is struck by the operator.

These and other objects are accomplished by means of the arrangement disclosed on the accompanying sheet of drawings, in which—

Figure 1 is a side elevation of a cartridge constructed in accordance with this invention;

Figure 2 is an enlarged cross sectional elevation of the left-hand end of the cartridge shown in Figure 1;

Figure 3 is a fragmentary view in vertical cross section of a portion of the mine wall and drill hole, showing the cartridge in place ready for blasting and the operating rod extending beyond the mine wall in a position to be manipulated by the operator.

The various novel features of the invention will be apparent from the following description and will be particularly pointed out in the appended claims.

By referring to the drawing it will be noted that the present disclosure only shows one end of the cartridge in detail, but, inasmuch as the present invention relates to a modified form of heating element and discharging means for cartridges of the type disclosed in our co-pending application, only those features which are essential to the understanding of the present invention are herein disclosed. For the other features, reference is made to the other application.

It will be further noted that the present invention is illustrated as applied to a cartridge having a rigid cylindrical casing 10, the cap members 11 and 12 on opposite ends thereof. The cap member 12 is provided with radial openings 13 on its periphery providing for the discharge of the cartridge in a manner described in the co-pending application. The rigid casing 10 is provided with a rigid wall 14 preferably integral throughout, having a threaded bore 15 centrally dis-

posed therein and the inlet passage 16 positioned to one side of the center. Located in the opening 15 is the sleeve 17, threaded as shown, and having the inwardly projected end 18 forming a mounting for the perforated tube 19 which houses the heating element 20.

Positioned in the sleeve is the elongated rod 21 having its inner end 22 terminating at a point slightly spaced from the detonating cap 23 at the end of the heating element 20. The interior diameter of the sleeve 17 is enlarged as at 24 and threaded as at 25 for receiving the packing gland which closely fits the rod 21 and by inward movement compresses the packing material 27 to effect a gas-tight seal around the rod, but permits slight longitudinal movement of the rod for the purpose of discharging the cap. The inlet passage 16 is enlarged as at 28 and screw-threaded so as to accommodate the stem 29 which has the inlet passage 30 in alignment with the passage 16 in the wall. The outer end of the stem is conical to provide a knife edge and is threaded to receive the valve sleeve member 31. The sleeve member is provided with screw-threads 32 on its inner surface for accommodating the valve 33, having a soft plug 54 at its inner end for engagement with the knife edge of the stem. The valve, of course, is adapted to take a key for manipulation on its outer end in the same manner as that shown in the co-pending application referred to. For filling the cartridge, it is obvious that a filling pipe may be attached to the inlet opening 34 and the valve 33 turned off of the knife edge seat, at which time fluid under pressure may be introduced through the passage 30-16.

When the cartridge is filled, it is merely necessary to turn the valve 33 on to its seat and to remove the nozzle from its pressure fit against the opening 34.

The end of the cylindrical casing adjacent the wall 14 is provided with a shoulder 35 threaded as at 36 to accommodate the casing or cap 11. The cap 11, at its outer end, has an opening 37 therein through which the rod extends. The rod 21 adjacent to portion where it passes through the opening 37 is screw-threaded as at 38 and is provided with a nut 39 engaging the end of the casing.

The purpose of this nut is to normally limit inward movement of the rod so as to prevent accidental discharge of the cartridge. However, this nut is adapted to release when a substantially predetermined force is exerted on the rod, such force being that which is normally employed in effecting an intentional discharge of the cartridge.

In the present example the heating element may be of any suitable character such as, for instance, chemical material consisting of metallic powders in the presence of oxidizing agents as for instance disclosed in

the co-pending application, or the charge may consist of black powder. It is preferable, but not necessary, to provide the ordinary detonating cap 23 set in the end of 5 a length of cordeau fuse 40, consisting of diluted T. N. T., enclosed in an envelope usually of lead or paper, the fuse setting off the chemical charge of black powder or some of the well known mixtures. In practice it 10 would not be necessary to have the fuse in the presence of black powder since the cap will set this off alone, but where the compound is not sensitive to a cap like, for instance, aluminum chlorate mixture, the fuse 15 is interposed.

It is also obvious that the cap may be replaced by a starter consisting of a suitable acid in a bottle or a suitable sparking device worked by friction. 20 From the above, it will be readily appreciated that the means herein proposed for discharging the cartridge are purely mechanical, that is, the initial impulse which starts the liberation of heat from the material 25 in the heating cartridge, regardless of whether the material is black powder or metallic powders and oxidizing agents mixed in proper proportions, is derived from the push or movement on a rod, for example, the 30 rod extending from the heating cartridge through a suitably tight gland in the wall of the rigid container, and further extending through the tamping which holds the shell or container in the drill hole in a coal or 35 other body which is to be broken down. This metallic rod or element further extends beyond the face of the coal or other body and is provided with means by which it is possible to actuate it in a longitudinal direction 40 and cause a blow to be struck upon a detonating cap, for example, which in turn ignites the heating charge supplying the heat necessary to increase the pressure of the 45 blasting medium to such an extent that the weaker wall or disk is ruptured. The actuation of the metallic rod to effect these means may be done by remote control so that the mine personnel is in no danger from flying coal or other material. 50 It is also contemplated that instead of extending the rod 21 entirely beyond the outside of the drill hole to be struck by the operator, a mechanical device of suitable construction such as a trigger held spring mounted 55 in the housing 11 may be provided, which mechanism may be tripped by means of a wire or other pulling element extending out of the drill hole to a remote location. Any 60 form of construction is contemplated in this use, it merely being necessary to provide a short construction rod positioned to be struck by a mechanically moved hammer or weight. In the operation of such a device the mechanical 65 discharging means will be cocked or set

prior to the insertion of the cartridge in the drill hole.

We claim:

1. A cartridge of the character described, comprising a casing and a movable discharging concussion rod extending into said casing and releasable means on said movable rod for holding said rod against accidental displacement said means being responsive to a predetermined force on said rod to permit 70 actuating movement of the same. 75

2. A cartridge of the character described, comprising a casing and a movable discharging concussion rod extending into said casing, a releasable nut on said rod in contact 80 with a portion of said casing to prevent accidental displacement of said rod. 85

3. A cartridge of the character described, comprising a casing adapted to contain a blasting medium under pressure, and having 85 a rigid wall, a sleeve threaded through said wall, a heating element attached to the inner end of said sleeve, and a concussion rod positioned through said sleeve having its inner end adjacent a cap for said heating element. 90

4. In a blasting cartridge, a casing having 95 an end wall with an aperture therethrough, a concussion rod extending through said aperture, a cap for the casing, said cap having an aperture through which said rod extends, and means on said rod adapted to co-act with said cap to prevent operative movement of the rod. 95

5. In a blasting cartridge, a casing having 100 an end wall with an aperture therethrough, a concussion rod extending through said aperture, a cap for the casing, said cap having an aperture through which said rod extends and means on said rod adapted to co-act with 105 said cap to prevent movement of the rod in response to subnormal impact thereon, said means being operative to permit movement of said rod in response to a normal impact. 105

6. A cartridge of the character described, comprising a rigid casing having an apertured end wall, a sleeve threaded through said aperture an igniting device supported by said sleeve within the casing, a reciprocable concussion rod extending through said sleeve and a packing gland in said sleeve surrounding the rod. 110 115
